CLAIM

The ornamental design for a female urination device, as shown and described.

DESCRIPTION

FIG. 1 is a front top perspective view of a female urination device showing my new design;

FIG. 2 is a front elevational view thereof;

FIG. 3 is a rear elevational view thereof;

FIG. 4 is a right-side elevational view thereof;

FIG. 5 is a left-side elevational view thereof;

FIG. 6 is a top plan view thereof;

FIG. 7 is a bottom plan view thereof;

FIG. 8 is a front top perspective view of a flattened configuration of the present invention;

FIG. 9 is a front elevational view thereof;

FIG. 10 is a rear elevational view thereof;

FIG. 11 is a right-side elevational view thereof;

FIG. 12 is a left-side elevational view thereof;

FIG. 13 is a top plan view thereof; and,

FIG. 14 is a bottom plan view thereof.

The broken line showing in FIGS. 1, 2, 3, 6, 7, 8, 9, 10 represent creases and form no part of the claimed design.

1 Claim, 14 Drawing Sheets(56)
